UNITED STATES PATENT OFFICE

RUSSELL D. WELLS, OF POTTSTOWN, PENNSYLVANIA

GAS RANGE

Application filed February 28, 1927. Serial No. 171,426.

One object of my invention is to devise a novel construction of a gas range, and more particularly to devise novel means for providing the doors with a fixed pivot instead of the customary offset pivot, or movable pivot.

Another object of my invention is to devise novel means to counterbalance the doors so that they will stay in any position to which 10 they have been moved.

With the above and other objects in view as will more clearly hereinafter appear, my invention comprehends a novel construction of a gas range and more particularly novel 15 means for hinging the doors so that they will have fixed pivots.

My invention further comprehends a novel construction and arrangement of door counterbalancing mechanism.

20 Other novel features of construction and advantage will hereinafter more clearly appear.

For the purpose of illustrating the invention, I have shown in the accompanying drawings a typical embodiment of it, which, in practice, will give satisfactory and reliable results. It is however, to be understood that the various instrumentalities of which my 25 invention consists can be variously arranged and organized and my invention is not limited to the exact arrangement and organization of these instrumentalities, as herein set forth.

Figure 1 is a sectional plan view of a gas 30 range embodying my invention.

Figure 2 is a top plan view of the rear end of a door in detached position.

Figure 3 is a section on line 3—3 of Figure 1.

40 Figure 4 is a detail of a pivot pin.

Similar numerals of reference indicate corresponding parts.

Referring to the drawings:—

45 1 designates a gas range embodying my invention. The gas range, in so far as the supporting frame-work, the arrangement of the burners, oven, and compartments is concerned, may be of any desired or conventional type. The stove is provided in the usual manner with the front standards 2 and the front

panel 3 having a door opening 4. The portion of the panel 3 which surrounds the door opening 4 is deflected inwardly and laterally as at 5 to form a seat for the door 6. The door 6 has extending rearwardly from it the arms 55 7 which are disposed at an angle to the plane of the door and are provided with an offset contact lug 8 which, when the door is opened to a horizontal position, will contact with the rear face of the panel 3 so that the door cannot be opened beyond its fully opened horizontal position, at which time it is preferably substantially flush with the bottom of the oven, as will be clear from Figure 3.

The door 6 is pivotally supported in a novel manner so that it will have fixed pivots instead of the customary offset pivots which latter have been deemed essential to provide for the outward movement of the bottom of the door when the door is opened.

60 9 designates L shaped pivot pins which pass through the arms 7 and are received in the apertures 10 formed in bosses 11, which are connected to or integral with the juxtaposed front standards 2. The rear marginal portion of the door is provided with recesses 12 near opposite sides of the door into which the pivot pins can be turned and the deflected portions of these pivot pins are disposed between the lining 13 and the door so that the door lining serves as a means to retain the 65 pivot pins 9 in their assembled position. The lining is secured to the door by means of fastening devices 14.

70 The front panel 3 is provided with the openings 15 through which the arms 7 extend and these openings are covered by the door when the latter is in closed position. It will be seen that the location of the pivots and their arrangement is such that the door

75 swings on fixed pivots instead of offset pivots, and when in closed position completely covers the door opening 4. The door lining 13 is spaced from the door proper by means of the lugs 16.

80 In order to counterbalance the door, one of the arms 7 is provided with a hook 17 to which is connected a chain 18, the chain passing downwardly around a pulley 19 which is carried by a bracket 20, secured to a stand-

95

100

ard 2. The chain then passes rearwardly and is connected with one end of a spring 21. The opposite end of this spring 21 is connected to a threaded eye bolt 22 which passes through the rear standard 23 and is provided with a nut 24 which enables one to vary the tension of the spring 21. It will thus be apparent that the door 6 is counterbalanced in such a manner that it will be retained in any position to which it is opened.

10 The door 6 is provided at its rear ends with the webs 15, at the opposite sides at the rear, the upper faces of said webs forming curved faces so that when the door 6 is in its opened 15 position the webs 25 will substantially fill the openings 15 in the front panel. These webs, or plates 25 may be integral with the sides of the door or connected thereto in any desired manner.

20 While I have illustrated and described the means for pivoting the oven door in position and counterbalancing it, it will be understood that the same construction is employed for the door which controls access to 25 the oven burner, and for other doors with which the gas range is provided.

Having thus described my invention what I claim as new and desire to secure by Letters Patent, is:—

30 1. A gas range having standards and a front wall provided with a door opening, a door to close said opening and having rearwardly extending arms, pivot pins passing through said arms and journaled on said 35 standards and having deflected portions, said door having means to limit longitudinal movement in one direction of said pins and a lining for the door overhanging said deflected portions to retain said pivot pins in 40 assembled position.

2. A gas range having standards and a front wall provided with a door opening, and with side openings adjacent opposite sides of said door opening, webs on the sides of said 45 door at its rear end to pass through and substantially fill said side openings, arms connected with the rear end of said door at the sides, and pivot pins for said door and carried by said standards in rear of said front 50 wall.

3. A gas range having standards and a front panel provided with a door opening, a door to close said opening and having rearwardly extending arms, said panel surrounding said door opening and being inwardly and laterally deflected to form a seat for the door and provided with side openings through which said arms extend, and pivot pins passing through said arms and journaled on said standards.

RUSSELL D. WELLS.
